UNITED STATES PATENT OFFICE.

JOSEPH H. ADAMS, OF FLATBUSH, NEW YORK, ASSIGNOR TO THE TEXAS COMPANY, OF HOUSTON, TEXAS, A CORPORATION OF TEXAS.

OIL-CONVERTING APPARATUS.

Application filed December 29, 1917. Serial No. 209,476.

To all whom it may concern:

Be it known that I, JOSEPH H. ADAMS, a citizen of the United States, residing at Flatbush, in the county of Kings and State 5 of New York, have invented a new and useful Oil-Converting Apparatus for the Conversion and Transformation of Oils, and of which the following is a specification.

This invention relates to improvement in 10 apparatus for converting oils and liquids, more especially oils of the hydro-carbon group into products of lower specific gravities and boiling points for the purpose of obtaining from inexpensive heavy oils 15 lighter oils such as naphthas; gasolenes, benzines, benzol, toluol and other light oils and oily spirits of both the plain and aromatic series by a process disclosed and claimed in my co-pending application filed of even date 20 herewith Serial No. 209,475.

One object of this invention is to provide a relatively simple and inexpensive means of internally applying heat under easy control to oils in atomized or finely divided 25 form for the purpose of altering their physical and chemical characteristics to a predetermined extent.

Another object within the contemplation 30 of this invention is to devise an apparatus which will not only facilitate the conversion of heavy and high boiling oils, such as kerosene, gas oil and other non-viscous neutral oils, into lighter oils and oily spirits but which will do so under conditions of 35 continuous operation thereby eliminating undesirable interruptions and other features prevalent in many types of so-called oil conversion apparatus.

This invention in general seeks to provide 40 an apparatus particularly adapted for "cracking" and transforming oils according to my process heretofore referred to, which, from an operative standpoint, will in practical usage, possess a high degree of efficiency and durability, and which, structurally considered, will be of the greatest possible simplicity in mechanical construction.

Other objects and advantages will be 45 pointed out in the following description. The invention accordingly consists in the features of construction, combination of elements and arrangement of parts which will be exemplified in the construction herein- 50 after set forth, and the scope of the appli-

cation of which will be indicated in the following claims.

The pressure on the vapors in the converter are self-generated from the expansion of heated oil sprayed in mist like or vaporous form in possible combination with high 60 temperature super-heated steam both of which are forced into the enclosed mixing and expansion chamber of the converter and rise in converted vapors and pass through the condenser preferably in open communication with the converter with means for controlling the discharge from the condenser or running trap tank located at the foot of or beyond the condensing coils, so as to regulate the predetermined super-atmospheric 70 pressure in the system.

In order that this invention may be the more fully understood and made comprehensible to others skilled in the art, drawings 75 illustrating the preferred adaptation of my apparatus are appended as a part of this disclosure.

In the annexed drawings, corresponding parts are similarly referred to by like characters of reference throughout the several 80 views of which:

Fig. 1, is a partially sectional elevation of a simple apparatus adapted for carrying out my process.

Fig. 2, is a similar view of another and 85 more complete apparatus embodying additional features.

Fig. 3, is a cross sectional view taken through line x—x of Fig. 2, showing the 90 electric heater and its relation to the cylindrical shell of the converter C.

Fig. 4, is a perspective view of the electric heater drawn to a larger scale and showing the structural details of the device.

Fig. 5, is a similar view of a modified structure embodying a double row of heating elements and showing how they are related.

Fig. 6, is a view corresponding to Fig. 1 95 of a modified form of apparatus which also constitutes an embodiment of my invention 100 and which is arranged for the application of external heat, and

Fig. 7, is the front elevation of a battery 105 of oil converting units showing the arrangement of a series of units for continuous commercial operation.

Referring to Fig. 1, A, represents a suitable supply tank which serves as a source of

the oil to be converted. Oil may be admitted into this tank by means of a supply pipe 1, controlled by valve 2, and withdrawn through a pipe 5, and forced by compressed air into the converter C, being controlled in its flow by precision valves 6. The height of oil in the supply tank A, can be seen in glass gauge 7, and should an air pressure be maintained over the surface of oil in the supply tank A, to force it into the converter C, against a back or vapor pressure in excess of atmospheric pressure, then the pressure gauge 8, at the top of tank A, will indicate such pressure. An air pipe 3, can be connected into the tank A, and controlled by valve 4, which pipe may be connected with an air compressor or other means of air pressure for furnishing the required pressure over the surface of oil in the tank A.

20 Inasmuch as it is desired to conserve heat energy as much as possible in this apparatus and bring the inflowing oil nearly to a vaporizing point the comparatively cold oil flowing through the pipe 5, is preferably caused to pass through an oil pre-heater B, and thus be raised in temperature before passing into the oil converting receptacle C. This pre-heater B, may comprise any suitable type of liquid heater but preferably provides a continuously rising coil 9, connected with the outlet pipe 10, which pipe is located at the top so that any air bubbles may readily escape and not form air locks in such pre-heating coil. The source of heat for said pre-heater may consist of any heat supplying means such as burner 85.

The drawing shows one of the many diverse forms which the converter C, may assume within the contemplation of this invention and such converter here shown comprises a closed retort or enclosure C surrounded by a cylindrical expansion and vapor separating dome D, provided with perforated baffle plates. The oil supply pipe 10, in this form leads into the upper part of the retort section C, which section forms the lower part of the converter and separator C—D, and is connected to the upper part, or vapor dome D, by means of 50 the neck 11.

Within the converter C, and located near the bottom, a heating grid of resistance elements 12, is supported upon insulators 13, and this heater or grid is supplied with energy from a source of electric current through cables +14 and -15, which pass through the bottom 16, of the converting chamber or retort C.

The oil admitted to the converter through pipe 10, is broken into spray or mist through sprinkler nozzles 17 and sieve 18, before coming into contact with or in close proximity to the electrically heated grid 12, which is maintained at a temperature sufficiently intense to convert and transform the

greater part or all of the oily mist or vaporized oil into a lighter vapor, which when condensed into liquid form will be essentially different from the original untreated oil.

The process of oil transformation as carried on in this apparatus by the application of intense heats employed to break up the high boiling oils into vapors of lower boiling products results in the production of certain percentages of fixed gases, according to the intensity of the heat and the nature of the original oil as well as the nature of the product sought. The apparatus is made to withstand relatively high temperatures and a superatmospheric pressure of 50 lbs. per square inch and upwards. The object of this apparatus is to render low boiling products from high boiling oils, and it is opposed to the production of large volumes of fixed gases.

From the top of the expansion and vapor dome D, an outlet pipe 19, is provided to lead out the light converted vapors and any fixed gases which may be generated during the process. This pipe connects into a vertical duct 20, which in turn leads to a condenser E, the coils 21, of which are in free communication with the converter as well as with a running trap tank F, by means of pipe 22, located at the foot of or beyond the condenser, and in which tank fixed gases and condensed vapors in the form of distillates are collected.

From this collecting tank F, fixed gases are withdrawn through pipe 23, controlled by valve 24, and pressures in the system are recorded on gauge 25, located at the top of this tank. Liquid distillates are withdrawn from the bottom of the tank through pipe 26, controlled by valve 27, and the height of oil in this tank can be observed by means of glass gauge 28, while the withdrawn gases may be collected in gas holder H, of which 29, is the sliding drum or movable dome holder.

During the operation of the apparatus some oil and oily spray may not come into contact or close relation with the electric heater 12, and such oils as pass below this grid will flow into the trap 30, located below the converter C, to which it is connected by means of neck 31. Particles of carbon separated during the process and any residues which might collect at the bottom of the converter, will naturally fall into the trap 30, and when oil rises therein to the height of the overflow pipe 32, it will flow into the hot oil overflow tank G, freely connected with the trap 30, by means of the pipe 32.

While the process is in operation, any heavy unconverted oily vapors mechanically carried over with the lighter vapors through pipe 19, and into pipe 20, will fall in pipe 20', pass through pipes 20" and 32, and be trapped in the tank G.

By means of glass gauges 33, located on tank G, the height of oil may be observed, and when it is desired to remove this oil through pipe 34 controlled by valve 35, the 5 pump 36, can be operated to withdraw it and return the same to tank A, through pipe 37, for re-treatment.

In practice, the application of heat to the 10 oily spray, while undergoing conversion, expands it and causes vapor pressure in all parts of the system not containing liquid oil, from the source of supply through to the end of or beyond the condenser including converter C, vapor dome D, condenser E, 15 gas and liquid tank F and also in the trap 30 and hot oil overflow tank G.

As a feature of safety in this high pressure system the blow off or release pop valve 60, is preferably located at a distance away 20 from the converter, usually above the condensing coils 21, as shown in Figures 1, 2, 6 and 7. The valve will release any sudden or excessive pressure above the pre-determined number of pounds to the square inch 25 necessary to assist in bringing about the desired conversion.

In the form of apparatus shown in Fig. 2, A, represents the main supply tank from which oil is supplied to the apparatus. This 30 tank can be filled through pipe 1 controlled by valve 2, and the oil is withdrawn through pipe 5, and forced by compressed air or by means of pump 38, through the pre-heater B, and into the converter C, being controlled 35 in its flow by precision valve 6. The height of oil in this supply tank can be seen in gauge glasses 7, and should air pressure be maintained over the surface of oil in the supply tank A, to force it into the converter 40 C—D, the pressure gauge 8, at the top of tank A, will indicate such pressure, and an air pipe 3 controlled by valve 4, may be connected to the top of the supply tank A, which pipe may lead to a source of compressed air, otherwise the oil is withdrawn 45 from the tank and forced into the converter C, through pre-heater B, by means of the pump 38.

This drawing shows another of the many 50 diverse forms which the converter C—D, may assume, and such converter here shown comprises a closed retort C, containing a heater 12, oil sprayer 17, protecting and confining sheath 39, sieve 18 and the necessary inlets and outlets for the continuous 55 operation of the process. Within this converter C—D and near the bottom, a grid of resistance elements 12, is located and supported on insulators 13, while above it and 60 within the sheath 39, there is placed a sieve 18, for the breaking up of oily spray into finer sprays or vapors. Above this sieve and near the top of the enclosed converter a pipe 10, is provided with a sprinkling system 65 composed of spray jets 17, at its top inner

end and located in such a position that oil sprayed from the jets will fall within the cone or sheath 39, to and through the sieve 18, and in close proximity to the electric heater 12.

The oil supply pipe 10, in this form of converter leads into the upper part of the retort section C, to the spray nozzles 17, and previous to its entry, the oil is brought to elevated temperatures in the pre-heater B, 70 in which coils of heating tubes are located and subjected to elevated temperatures by any economical means of heat. The oil so admitted is broken into a spray or mist through sprinklers 17, and any undivided 75 particles of oil will be further broken up as it passes through sieve 18, before reaching the heater 12. The converted spray and some of the unconverted oil driven into 80 vaporous form by the intense heat rises 85 through neck 11, into expansion and vapor dome D, where the heavier vapors in part come in contact with the perforated baffle plates 40, are condensed and drop back to the bottom of the dome D, and which, by 90 means of the dished bottom, are led through neck 11, to a collar 41, from which they drip to the outside of the sheath 39, and flow down the outer surface of this sheath toward the intensely heated zone where the oil may 95 be transformed into lighter oily vapors.

The lighter converted parts of the vapors escaping through the perforations in the baffle plates 40, are led out through pipe 19, at the top of the dome D, and into vertical 100 pipe 20, and so on into the condenser E, where, in the coils 21, the vapors are reduced to distillates.

The condenser E, as shown, is in free communication with the converter C—D, as well 105 as with the distillate receiving trap tank F, by means of pipe 22, and which tank is located at the foot of or beyond the condenser. In this apparatus, as well as in that shown in Fig. 1, any heavy vapors 110 which are mechanically carried through the dome D, and out through pipe 19, into pipe 20, and which may condense in the pipes, can flow down through pipe 20', into the chamber 30, or tank G, and be returned to the 115 system for re-treatment as before.

Fixed gases generated during the operation of this apparatus are collected also in tank F, and can be withdrawn from time to time intermittently, or continuously released by means of pipe 23 regulated by valve 24, and the vapor pressure in the system, which have to be kept at a uniform 120 number of pounds to the square inch for best results, can be recorded on gauge 25.

Distillates are withdrawn from the bottom of the tank F, through pipe 26, controlled by valve 27, and the height of oil in the tank can be observed in glass gauge 28. When such distillate is removed from the 130

tank, pump 42, may be put into operation to deliver the distillate in any direction desired through pipe 43. Oils which are not broken up into vaporous form and such as 5 pass below the heater 12, in the converter C, will flow into the trap 30, located below the converter, to which it is connected by means of a neck 31.

Carbon and other residues formed during 10 the operation of the apparatus, and which collect at the bottom of the converter, will naturally fall or be swept into trap 30, and when oil rises to the height of the overflow pipe 32, it will flow into the hot oil tank G. 15 Glass sight gauges 33, located on this tank will show the height of oil, and when it is necessary to remove this oil to make room for that which is continuously flowing in, the pump 36, can be operated to withdraw 20 oil through pipe 34 controlled by valve 35, and return it to tank A, through pipe 37 for re-treatment.

In addition to maintaining compressed air over the surface of the oil in tank A, for 25 delivering it into the system and as a means instrumental for delivering the raw oil from tank A, into the converter C—D, through pre-heater B, the pump 38, is operated at any speed desired to maintain a constant and 30 steady flow, but as it would not be possible to so rapidly pass all of the oil through the system that the pump would draw and force, it is necessary to return a certain portion of the oil to the tank A. This is accomplished by closing the valve 44, so that 35 the oil may be drawn through pipe 5, by the pump 38, and forced into the converter through the precision valves 6, and any oil not admitted into the converter flows up 40 through pipe 45, and passes through an enclosed pop or release valve 46, and by means of the upper part of pipe 37, is returned to the tank A.

If, for instance, a back or vapor pressure 45 of seventy-five pounds to the square inch is maintained in the system and it is desired to force oil into the converter through pump 38, it is necessary to set the release valve 46, at 50 90 to 100 pounds to the square inch so that the oil can be forced against a check set at a higher pressure than that maintained in the system, and in this manner it is not necessary to operate the pump at any particular speed for any excess oil above the 55 quantity admitted into the system through the precision valves 6, is, by this means, returned to the original supply tank.

In the commercial operation of my process heretofore referred to in an apparatus 60 of this nature it may here be pointed out that when operating upon certain classes of oils, that is the more volatile oils, it is highly desirable to localize the application of the intense internal, or possible external, heat 65 so as to prevent the spread of the heat in a

lower degree of intensity than is necessary to efficiently crack the oily spray, but of sufficient intensity to cause the vaporization of undue amounts of the oily spray at a distance from the electric heater without 70 bringing about a conversion.

It is also desirable to treat the oil as rapidly and thoroughly as possible and not to drive over and through the condenser any more of the un-converted vapors of oils than 75 is absolutely unavoidable. To this end I have provided a sheath 39, which confines the supplied oily spray and which spray must pass down and out from the bottom of the sheath before it can rise in vaporous or 80 gaseous form into the upper part of the converter C, and into the dome D. The spaces below the lower edge of the sheath 39, and the heater 12, permits the escape and rise of both converted and un-converted vapors, as 85 indicated by the arrows, into the expansion and vapor separating dome D, where the heavier vapors are dephlegmated and drop back into the converter C, for re-treatment.

As an added feature of importance in this 90 method and apparatus for oily vapor transformation I may also employ super-heated steam which is injected at elevated temperatures into the body of the oily vapors undergoing treatment, through pipe 56, controlled by valve 57 and admitted in finely 95 divided streams through jets 58.

The steam is generated and preferably 100 super-heated to a temperature of from 800° to 1,000° F. outside the apparatus but is introduced within the sheath 39, for the purpose of assisting conversion, hydrogenating the transformed vapors and taking off some of the carbon residue from the process and out of this apparatus in the form of carbon-dioxide, carbon-monoxide and other fixed 105 gases.

The construction of the grid or electric heater can be quite clearly seen in Fig. 3, where the heating elements are alternately 110 joined at their ends by heavy connecting links, thus enabling electric current to flow from one to another, and this form of grid permits of an otherwise long strip or rod of resistance material being confined in a 115 small area. This grid rests on insulators 13, of soapstone, porcelain or other suitable material and is somewhat elevated above the bottom of the retort to prevent contact with any parts of the container or carbon fractions which may split off and drop from the electrodes.

The structural details of this electric heater as made up from a series of carbon rods is quite clearly shown in Fig. 4, and the electric current flows in through cable 125 +14 and passes successively through the resistance rods which, are screw threaded at their opposite ends to engage clamp nuts such as 67 and 68. The current passes 130

through the resistance rod 65, then across link 69, then through the adjacent rod 70, then across link 71 and through rod 72, continues to progress through all of the rods and links comprising the heater then finally passes out from the last rod to the negative conductor -15 (as shown in Fig. 3).

It will be perceived from the foregoing that, by this arrangement each of the rods 10 65, 70, 72 and all of the others composing the grid will carry the same current, and as they are constructed of like resistance members they will be evenly and equally heated by such current. Furthermore, by controlling 15 the electric current, these rods or electrodes may be maintained at any pre-determined temperature even though completely submerged in oil. This constitutes a feature of the greatest importance in my invention.

20 Inasmuch as the precise degree of temperature at which the electric heater should be maintained will be dependent upon and will vary with the particular conditions, I may state that the temperature will, in practice, ordinarily vary from a high black heat to incandescence, according to the fluid treated.

When operating in this manner it has been observed that only a part of the vapors 30 coming in close proximity to the heater are actually converted for the reason that the conduction of heat is sufficient to evaporate a certain portion at a lower temperature than is requisite for the "cracking" of the oil. 35 Accordingly, the vapors passing into the dome will be composed not only of the oily vapors which have been converted by the breaking up of its molecules by the high heat, but will contain, as well, a certain proportion of the original oil. The separation 40 of the lighter from the heavier is therefore the object of the separating dome D.

The drawing Fig. 5, represents an end view of a heater showing a double row of 45 resistance rods the upper tier alternating with the spaces between the rods in the lower tier so that a uniform radiation of heat can be had. The rods are broken in this drawing just beyond the links as the attachment 50 and arrangement of links at the opposite ends will be understood by the drawings Figs. 3 and 4.

As heretofore described, the current passing in through feeder cable +14, terminal 55 66, rod 65 then through rods 70, 72 and so on to the end of the grid will then return through the resistance rods and links of the upper tier as 73, 74, 75, 76, 77, 78, 79 and so on to the end where the current will flow 60 out through cable -15 as described. In these double tiers it is necessary to separate and hold securely the two lines of rods and this is best done by inserting porcelain tubes between the tiers at their ends or clamping 65 mica links as 80, under the nuts 81, which

hold the links and the ends of the rods securely in place. This latter method prevents the accumulation of any particles of carbon which may fall from the electrodes and which might cause a short circuit and in the 70 construction of the heater and assembling of the parts these mica links are easily placed in position and held by the nuts securing the rods in the desired position.

Referring now to Fig. 6, it will be seen 75 that all of the principal parts of apparatus here shown resemble those shown in Fig. 2, and are co-related for the purpose heretofore described. The heater and heating means, however, are different, the heat being 80 applied externally to the bottom of a dished plate or disk near which the oily spray is transformed and converted into vapors of dis-similar nature.

The supply tank A, pre-heater B, converter C—D, condenser E and trap tank F, as well as the hot oil overflow tank G, are all arranged about as shown in the apparatus of Figs. 1 and 2, but in carrying off the surplus unconverted oil a different means 90 has been adopted as will be described.

To provide an economical means of heat where electric current is not available or is too high in cost for commercial usage, the dished plate 47, is attached to the lower 95 part of the shell of the converter C, by means of bolts drawn against a heat and hot oil proof gasket of asbestos or other suitable material. The converter C, is mounted above a furnace J, constructed of suitable 100 fire brick and provided with a bridge wall 48, against which the elements of combustion are projected from a burner 49. The heat from such combustion rises to the top of the furnace and heats the plate 47, to 105 cracking temperature so that the oily vapors or sprays from the jets 17, must come in close proximity to this highly heated surface before escaping into the dome D.

The heat so generated must rise and heat 110 the plate 47, from the under side before it can flow down and out through the flue 50, of the stack 51, which stack is provided with damper 52, for the purpose of properly regulating the heat held within the furnace J, 115 and duct 63, is provided to lead the gases of combustion above the apparatus.

In order to provide a means for the escape of unconverted oil which might accumulate 120 at the lower part of converter C, in the valley around the outer part of the plate 47, and below the crowned part, pipe 53, is provided to connect into the lower end of pipe 20', in order to lead this oil into hot oil overflow tank G, through pipe 32.

125 Since it becomes necessary only to provide a simple and inexpensive means of heat for carrying out the process of vapor or spray conversion, the drawing Fig. 6, shows the adaptability of this form of externally 130

applied source of heat to bring about the desired results.

The battery of converters shown in Fig. 7, illustrate a commercial installation of units 5 for carrying on my process and while there are but three units shown in this drawing, any number of such units may be arranged in batteries, each unit leading into the main vapor duct 54, leading to the condenser or 10 condensers E.

A feature of importance in the arrangement of a number of units in a battery as shown, is in the fact that through the vapor line, or other equalizing pipe or pipes as 59, 15 all of the units carry the same uniform vapor pressure, for by such duct and the pipes 19 and 20, as well as the descending pipes 55, the pressure in each unit is compensated or 20 equalized one with another and in this manner, while one furnace may be slightly hotter than another, the pressure maintained over the oil in the converters and in the vapors being condensed is the same in all of 25 the units comprising such a system, then also, should it be necessary to make repairs or shut down any one of the units this can be done by closing the oil supply valve and the vapor line valve as well as the hot oil 30 overflow line valve and the unit needing attention can be taken care of without disturbing the continuous operation of the other units comprising the system.

The inflowing oil to the converters being preferably pre-heated is led through pipe 35 61, and controlled at its entry into each converter by valves, as 62, with which an accurate delivery of oil can be made instead of having one valve to control the entire inlet system.

40 In view of the foregoing disclosure, it will be obvious to those skilled in the art that my apparatus may be operated with different base materials and with different fluids from those specifically referred to, by various 45 steps, and with the assistance of different apparatus without, however, departing from the scope of my invention, and accordingly I intend that all matter contained in the above description shall be interpreted as 50 illustrative and not in a limited sense.

I desire it also to be understood that the language adopted in the following claims is intended to cover all of the generic and specific features of the herein described invention and all statements of the scope thereof as a matter of language might be said to fall therebetween.

Having described my invention what I claim and desire to secure by Letters Patent is:

1. In an oil treating apparatus, the combination with means for spraying oil in atomized or finely divided form into a closed chamber under pressure, means disposed 65 outside said chamber for preheating the oil

to a comparatively high temperature below vaporization, a heating member within the chamber adapted to subject the compressed atomized oil to a cracking temperature, and means for condensing converted vapors under superatmospheric pressure. 70

2. In an oil treating apparatus, the combination with means for spraying oil in atomized or finely divided form against a back pressure into a closed chamber, means 75 disposed outside said chamber for preheating the oil to a comparatively high temperature below vaporization, a heating member within the closed chamber against which the oil spray is projected, said heating member being maintained at a cracking temperature, and means for condensing the cracked vapors under superatmospheric pressure. 80

3. An apparatus of the nature disclosed 85 comprising in combination a converting chamber, a bell-shaped sheath mounted in said chamber leaving spaces between it and the walls of the chamber, means for spraying oil downwardly in fine streams within said sheath under pressure, a heater below said sheath against which said sprayed oil is directed, pipe connection at the top of said converter to carry away vapors and gases, pipe connection at the bottom for 90 carrying away residue and liquid products in said converter, and means for maintaining pressure in said converter. 95

4. An apparatus of the nature disclosed 100 comprising in combination a converting chamber, a bell shaped sheath mounted in said chamber leaving spaces between it and the walls of the chamber, means for spraying oil downwardly in fine streams within said sheath under pressure, a perforated 105 screen in said sheath below said spraying means through which said sprayed oil passes.

5. An apparatus of the nature disclosed 110 comprising in combination a converting chamber, a bell shaped sheath mounted in said chamber leaving spaces between it and the walls of the chamber, means for spraying oil downwardly in fine streams within said sheath under pressure, a heater below 115 said sheath against which said sprayed oil is directed, an expansion dome for vapors above said converter, a pipe connection between the bottom of said dome and the top of said converter the parts being so arranged that material condensing in said dome will flow back into said converter, means for taking off and condensing the vapors in said dome, means for collecting and conveying away condensed liquid at the 120 bottom of said converter and means for maintaining superatmospheric pressure in said converter and dome. 125

6. An apparatus of the nature disclosed 130 comprising in combination a converting

- chamber, a bell shaped sheath mounted in said chamber leaving spaces between it and the walls of the chamber, means for spraying oil downwardly in fine streams within 5 said sheath under pressure, a heater below said sheath against which said sprayed oil is directed, an expansion dome for vapors above said converter, baffle plates in said dome, a pipe connection between the bottom 10 of said dome and the top of said converter the parts being so arranged that material condensing in said dome will flow back into said converter, means for taking off and condensing the vapors in said dome, means 15 for collecting and conveying away condensed liquid at the bottom of said converter and means for maintaining superatmospheric pressure in said converter and dome.
- 20 7. An apparatus of the nature disclosed comprising in combination a converting chamber, means for continuously supplying oil to said chamber under pressure, means for preheating the oil before it enters said 25 chamber, means for causing said oil to be discharged downwardly in numerous finely divided streams within said chamber, a heating member towards and against which said streams are discharged, means for 30 maintaining said heating member at such temperature as to vaporize and convert the oil streams, a vapor expansion dome above said chamber connected thereto whereby material condensed in said dome will return 35 to said chamber, means for drawing off material from the bottom of the chamber, means for maintaining vapor pressure in said chamber and dome and means for taking off and condensing the vapors in said 40 dome.
- 45 8. An apparatus of the nature disclosed comprising in combination a converting chamber, means for continuously supplying oil to said chamber under pressure, means for preheating the oil before it enters said chamber, means for causing said oil to be discharged downwardly in numerous finely divided streams within said chamber, a heating member 50 towards and against which said streams are discharged, means for maintaining said heating member at such temperature as to vaporize and convert the oil, a vapor expansion dome above said chamber connected thereto whereby material condensed in said 55 dome will return to said chamber, means for drawing off material from the bottom of the chamber, a condenser freely connected with said dome, and means for maintaining substantially the same superatmospheric pressure in said converter dome and to and through the condenser.
- 60 9. An apparatus of the nature disclosed comprising in combination a converting chamber, means for continuously supplying 65
- oil to said chamber under pressure, means for preheating the oil before it enters said chamber, means for causing said oil to be discharged downwardly in numerous finely divided streams within said chamber, a heating member 70 towards and against which said streams are discharged, means for maintaining said heating member at such temperature as to vaporize and convert the oil, a vapor expansion dome above said chamber connected thereto whereby material condensed in said dome will return to said chamber, means for drawing off material from the bottom of the chamber, a condenser freely connected with said dome, and means for maintaining substantially the same superatmospheric pressure in said converter dome and to and through the condenser.
- 75 10. An apparatus of the nature disclosed comprising in combination a converting chamber, means for continuously supplying oil to said chamber under pressure, means for causing said oil to be discharged in jet form in said chamber, a heating member towards and against which said jets are discharged, means for maintaining said member at such temperature as to vaporize and convert the oil, pipe connection leading from the bottom of said chamber and a trap tank into which it discharges, an enlarged vapor dome above and connected to said chamber, a condenser in free and open connection 80 with said dome, means for separating the unconverted material from the converted vapors between said dome and condenser and for conveying the unconverted material to said trap tank and means for maintaining substantially the same superatmospheric pressure throughout the system to and including the condenser.
- 85 11. An apparatus of the nature disclosed comprising in combination a converting chamber, a bell-shaped sheath mounted in the chamber leaving spaces between it and the walls thereof, means for spraying oil downwardly in fine streams within said sheath under pressure, and a heater disposed beneath said sheath and maintained at a cracking temperature for converting the sprayed oil.
- 90 12. An apparatus of the nature disclosed comprising in combination a pressure chamber having a residue outlet at the bottom and a vapor outlet at the top, means disposed within and at the top of the chamber for spraying heated oil downwardly under pressure, means connected to the residue outlet for withdrawing and collecting the residue, an electric heater maintained at a cracking temperature mounted within said chamber between the spraying means and the residue outlet and against which the oil 95
- 100 105 110 115 120 125 130

is sprayed and by which it is cracked, and a perforated screen interposed between the spraying means and the heater.

13. An apparatus of the nature disclosed comprising in combination a pressure chamber, means for preheating oil and spraying it in finely divided form downwardly in said chamber, means for spraying superheated steam downwardly therein and mixing it with the sprayed oil, means for locally confining the mixture and directing its flow, and heating means maintained at a cracking temperature disposed below said confining and directing means for converting the sprayed oil.

14. An apparatus of the nature disclosed comprising in combination a series of pressure units severally comprising lower cracking chambers and upper vapor-separating

chambers, means for concurrently supplying heated oil to the several cracking chambers and spraying it under pressure in finely divided streams therein, heating members associated with the several cracking chambers and maintained at cracking temperatures for converting the oil sprayed therein, means for removing the evolved vapors from the vapor-separating chambers, and means for establishing free and open communication between the upper vapor separating chambers to equalize the vapor pressures developed in the several units.

In testimony whereof I affix my signature in the presence of two witnesses.

JOSEPH H. ADAMS.
